SYSTEM OF PULVERIZING, FEEDING, AND
TRANSPORTING OF MATERIALJames L. Harvey, Wadsworth, Ohio, assignor to
The Babcock & Wilcox Company, Rockleigh,
N. J., a corporation of New Jersey

Application May 22, 1943, Serial No. 488,013

12 Claims. (Cl. 241—34)

1

The invention disclosed herein pertains to a system providing for the pulverization of a solid material capable of being transported in a finely divided state by means of a current of air or other gaseous medium. The material may suitably be a fuel such as coal, although other fuels, or other materials of a non-combustible character, are equally within the scope of the invention. The invention further contemplates transportation of the pulverized product to one or more points of use.

A specific application of the invention is to an air-swept pulverizing and distributing system wherein a current of air or other gaseous medium is maintained throughout the system for removing pulverized fuel from a pulverizer and for transporting the pulverized fuel direct to one or more burners in the manner commonly referred to as "direct-firing." Nevertheless certain features of the invention may be found useful in other known systems employing such additional apparatus as cyclones, storage bins, and feeders incident to the transportation of the pulverized material from the pulverizer to the ultimate point of use.

In a direct-fired system employing a plurality of burners in one or more furnaces, it may often be found desirable to utilize a single pulverizer for supplying the entire fuel requirements of several burners operating simultaneously. Where a number of small furnaces are involved, it may also be found both convenient and economical to distribute fuel to the burners of several furnaces from a single continuous main conduit system having both ends connected to the pulverizer to provide a closed circulating path or circuit for the fluent fuel mixture; individual burners being supplied through individual branch lines connected to the conduit at intervals along its length, and any surplus quantity of the mixture above that required by the burner or burners in operation being returned in whole or in part to the pulverizer or other advance point in the system for recycling.

If one or more burners should be operated at varying capacities, or if the cycles of operation of individual burners should be different, the resulting changes in overall fuel consumption make it necessary to provide suitable adjustment of the rate at which material is fed to the pulverizer. Such conditions may be found in metallurgical plants, for example, where a different number of furnaces for the same or different processes may be in operation over different periods, thus causing abrupt and wide variations in fuel consumption for which there must be adequate control of pulverizer operation to suit each new condition.

In the usual direct-fired system where the entire output of the pulverizer is utilized and none of the mixture is returned for recycling, it has

2

been found that the quantity of pulverized coal discharged from the pulverizer is substantially proportional to the rate of flow of primary air therethrough so long as a proportional amount of coal is maintained therein. This characteristic of air-swept pulverizer operation is utilized in U. S. Patent 1,965,643 to R. M. Hardgrove whereby the feed of material to the pulverizer is controlled to maintain a certain level or reserve quantity of material in the pulverizer for the existing rate of flow of primary air.

According to the present invention, an air-swept pulverizer and transport system is proposed wherein any desired proportion of the pulverizer output may be withdrawn, and any remaining proportion circulated by being returned to the pulverizer, or in part to the pulverizer and in part to some other point in the system in advance of a point of withdrawal, the proportions of the mixture so withdrawn and returned being varied as desired for a given value of pulverizer output, or for different values.

As an accompaniment to such an objective, it is proposed to maintain under all conditions a proper relation between fuel and air in the mixture available for withdrawal.

An additional object concerns the supply of raw material to the system and the maintenance of a proper reserve of material in the process of pulverization within the pulverizer, each in relation to varying demands on the system.

Another object contemplates controlling the rate at which raw material is fed to the pulverizer in accordance with fluid flow conditions within the system, including for example, the rate at which a portion of the pulverizer output is returned for recycling.

A further object is to correlate indications of fluid pressure conditions existing at different points in the system for the purpose of controlling pulverizer operation.

These and other related objects of the invention may be achieved in the manner about to be described, an arrangement of apparatus suitable for the purposes of the invention being diagrammatically indicated in the accompanying drawing.

In the drawing, an air-swept pulverizer 10 is shown with its associated feeder 12 by which raw unpulverized material such as coal, is fed to the pulverizer from a suitable bin 14 or other source of supply, the feeder being driven by a multi-speed electric motor 16, for example, as a means of providing different rates of feed.

Air or other gaseous medium to provide a carrier for the pulverized material is admitted to the pulverizer through an inlet duct 18 by which the carrier medium at an elevated temperature is supplied from a source not shown, a branch inlet 20 conveniently open to the atmosphere pro-

viding a means for admitting tempering air to the duct 18; regulating dampers 22 and 24 being suitably provided in the respective inlet connections for maintaining the temperature of the carrier medium entering the pulverizer at a desired predetermined value.

A fan 26 connected to the pulverizer outlet by the discharge duct 28 induces a draft through the pulverizer which causes the carrier air to pass into the pulverizer from the duct 18 and to pass through the pulverizer where it picks up the pulverized material to provide a fluent mixture, which for the purpose of this example may consist of pulverized fuel suspended in a stream of primary combustion air, the term "air" being used generally whether or not a portion of the carrier medium is obtained, as is sometimes the case, from a source of hot flue gases. The mixture is discharged from the pulverizer through the duct 28 as a fluent stream, passing through the fan 26 and into the fuel main 30 from which it is delivered to one or more points of use.

The illustrated embodiment provides for delivery of the pulverulent fuel mixture to a plurality of burners 32, 34, 36 and 38 associated with a plurality of furnaces 40, 42 and 44, each burner line 46 preferably being fitted with a plug valve 48 adjacent its connection to the fuel main 30, and with a second valve 50 of the butterfly type intermediate the plug valve and the burner. The plug valves are for the purpose of cutting off and completely isolating the supply of fuel from individual burners so that any number of burners may be operated, as desired, while the butterfly valves serve as a means for regulating the flow of fuel to such burners as are in operation. In practice, the fuel main 30 may be so arranged that the greater part of its length is horizontally disposed and at a level higher than the level at which the burners are located, thus enabling the burner lines 46 to be conveniently connected to the under side of the fuel main 30 and to extend vertically downward therefrom for connection to individual burners. A secondary supply of air may be admitted to the burners or to the furnaces for combustion purposes, but the details of such secondary supply do not enter into the subject of the present invention and are therefore omitted from the drawing.

The fuel main 30 is continued beyond the last burner to be served, here indicated as burner 38 for furnace 44, to provide a conduit length 52 for returning to the pulverizer any surplus quantity of the fuel-air mixture which is not delivered to the burners, the return length 52, as shown, being connected to the pulverizer 10 at a location opposite to the location at which the primary air is admitted through duct 18, and at a somewhat higher level. There is thus provided a single continuous main conduit system consisting of the discharge duct 28, fan 26 and fuel main 30 including its return length 52, having both ends connected to the pulverizer 10 and thereby forming a closed path or circuit over which at least a portion of the mixture initially discharged from the pulverizer may be circulated. The fuel main 30 may be formed of different sizes of conduit with reductions in cross section at intervals as at 54, 56 and 58 to maintain a sufficiently high velocity of fluid flow throughout to prevent fuel from settling out of the flowing mixture.

The pulverizer shown is of a known type utilizing a circular series of steel balls 60 operating between a stationary lower grinding ring 62 and a revolving upper grinding ring 64, the latter

being operatively connected to the rotating spindle 66 to which an extension casting 68 is fitted to provide an annular passage or throat 70 for directing the carrier air into the grinding zone. A duct 72, formed in the base of the pulverizer and open at its upper side to the throat 70, provides a mixing chamber for fresh incoming primary air entering at one end from inlet duct 18 and for the surplus fuel-air mixture entering at a location adjacent its opposite end from the return line 52. The introduction of the surplus mixture at the level indicated takes advantage of the conical formation of the pulverizer casing as at 74 which serves to deflect the returning mixture downwardly into the duct 72 and obliquely against its bottom wall, thus producing a degree of agitation which tends to promote a redistribution of the fuel particles within the chamber and a more thorough mingling of the two streams to provide a relatively homogeneous total mixture of fuel and primary air for admission through the annular throat 70.

It is evident that in the operation of a direct-fired circulating system such as has been described, there can be wide variations in fuel consumption due to the ability to operate a different number of burners at different times, and, if necessary, to operate individual burners at varying capacities. The resulting variations in fuel consumption impose varying demands on the pulverizer unit so that it becomes necessary to increase or decrease the rate at which raw coal is fed to the pulverizer, such changes in load requiring a change in the rate of fuel input which while satisfying the demand for a different output of pulverized fuel will also maintain the proper level or reserve of material in the pulverizer for the particular load involved; the level of material being preferably increased as the load is increased and decreased as the load is decreased.

Since the pulverized fuel is maintained throughout the system in a fluent state, that is, in suspension in a current of primary air or other gaseous carrier medium, an indication may be obtained of the rate of flow of the fluent fuel mixture through a given portion of the system by measuring the pressure differential across that particular portion. A similar measure may be obtained of the rate at which air is supplied to the system. These are factors which enter into the control of pulverizer operation in the present system.

Referring again to the drawing, a measure of air flow to the pulverizer is conveniently obtained by employing an orifice 76 in the inlet duct 18, the resulting differential pressure across the orifice being transmitted by tubes 78 and 80 to the pressure sensitive diaphragm 82 suitably mounted for movement within a stationary casing 84. The pressure differential resulting from the flow of air and coal in suspension through a selected portion of the pulverizer, including particularly the grinding zone thereof, is transmitted by tubes 86 and 88 to the pressure sensitive diaphragm 90 within the casing 92, the tube 86 being connected to a pressure point in advance of the grinding zone, for convenience to the downstream side of the orifice 76 as in the case of tube 80 for diaphragm 82, and tube 88 being connected to a pressure point following the grinding zone, for convenience to a point adjacent the pulverizer outlet. The rate at which surplus fuel and air are returned to the pulverizer under varying conditions is

measured in terms of the pressure differential across a selected portion of the return conduit 52, tubes 94 and 96 being connected to the conduit at relatively widely separated locations and the existing pressure differential transmitted thereby to the pressure sensitive diaphragm 98 within the casing 100.

The relative pressures acting upon diaphragm 82, 90 and 98 are coordinately utilized to effect movement of the lever 102 which is pivoted about a point 104 fixed in relation to the casing 84 at one side. The lever 102 carries a contactor element 106 whereby upon movement of the lever 102 about its pivot point 104 certain electrical circuits to be later described are selectively energized to control the operation of the feeder motor 16 and thereby the rate at which coal is fed to the pulverizer.

The force exerted by diaphragm 82 is transmitted to the lever 102 by means of a pin 108 movable with the diaphragm 82 and extending through opposite walls of the casing 84, one end of the pin engaging the lever 102 at a predetermined distance from the fulcrum point 104. The opposite end of pin 108 engages a second pivoted lever 110 also at a predetermined distance from a fixed fulcrum point 112, the lever arm distances in both instances being suitably equal as shown.

The force exerted by diaphragm 90 is applied to the lever 102 by means of a pin 114 extending through a side wall of casing 92, and similarly, the force exerted by diaphragm 98 is applied to the lever 110 by means of a pin 116 extending through a side wall of casing 100. The casings 92 and 100 preferably have adjustable mountings as at 118 and 120, whereby their positions may be varied relative to the respective fulcrum points 104 and 112, to thus increase or decrease the lever arm distances at which the forces exerted by diaphragms 90 and 98 are applied to the respective levers 102 and 110.

Springs 122 and 124 are provided to apply an initial loading to the levers 102 and 110 respectively, each spring having an adjustment 126 by which a desired degree of tension or compression may be obtained.

It may be assumed that the burners shown are of such capacities that when all are operating simultaneously at full ratings the total delivery of fuel and air to the burners is practically equal to the total output of fuel and air from the pulverizer, in which case there is a minimum of surplus fuel and air being returned to the pulverizer and the differential pressure transmitted through tubes 94 and 96 approaches zero. Under such conditions, virtually clean air alone is admitted through the pulverizer throat and, in accordance with known characteristics of air-swept pulverizer operation, the differential pressure across the clean air orifice 76, as transmitted through tubes 78, 80 to diaphragm 82, bears a definite relation to the differential pressure across the pulverizer 10, as transmitted through tubes 86, 88 to diaphragm 90; this relation being determined by the pulverizer design and the grindability, sizing, and moisture content of the fuel being handled. As long as the fuel characteristics remain the same, and air flow through the pulverizer is kept constant, the pressure differential across the pulverizer cannot be increased or decreased without an accompanying increase or decrease of the pulverizer output; and conversely, the pulverizer output cannot be increased or decreased without an accompanying

increase or decrease of the pressure differential across the pulverizer.

Therefore, with return flow through conduit 52 practically zero, the entire control of pulverizer operation is subject to the relative forces exerted by diaphragms 82 and 90 on lever 102, whereby motor 16 will be operated at intervals at the proper speeds to provide a fuel-air mixture of a predetermined fuel-air ratio at the required pulverizer output; the term "fuel-air ratio" being defined as the cubic feet of air at pulverizer outlet temperature per pound of fuel.

When the opposing forces exerted on lever 102 by the diaphragms 82 and 90 are balanced, the contactor 106 is held clear of all upper and lower contacts 140, 142, 144 and 146, and feeder 12 is operated to feed material to the pulverizer at a predetermined "low" rate. If the level or reserve quantity of material within the pulverizer should decrease, thus decreasing differential pressure across the pulverizer, the force exerted by diaphragm 82 overcomes the force exerted by diaphragm 90, and lever 102 is moved counterclockwise to cause contactor 106 to successively contact the upper contacts 140 and 142, and feeder 12 is operated to feed material to the pulverizer at a predetermined "high" rate to restore the normal operating level for the required rate of pulverizer output. If the level or reserve quantity of material within the pulverizer should increase beyond the normal operating level, the differential pressure across the pulverizer is correspondingly increased, and the force exerted by diaphragm 90 overcomes the force exerted by diaphragm 82, and lever 102 is moved clockwise to cause contactor 106 to successively contact the lower contacts 144 and 146, and operation of feeder 12 ceases.

When operation of the system is such that an appreciable flow of the pulverized material and air mixture occurs in the return line 52, the density of the fluid admitted through the pulverizer throat 70 is increased and the same relation of pulverizer differential to fresh air differential no longer holds. Furthermore the new relation may be subject to variations due to the varying rates at which the mixture is returned, and to the relation which the proportion of the mixture returned bears to the total pulverizer output for a given load.

Assuming one of the burners, burner 32 for example, to be shut off, the proportion of the total pulverizer output formerly delivered to that burner becomes a surplus proportion of the total mixture which is returned through conduit 52 to the pulverizer 10 where it is mingled with the fresh air entering through inlet 18 for combined flow through the pulverizer throat 70, the resultant modified mixture constituting in effect a modified carrier medium of increased density. Tests have indicated that when an appreciable proportion of the mixture is returned to the pulverizer, as through the conduit 52, the relation between the differential pressure across the pulverizer and the differential pressure across the clean air orifice 76 is modified, as compared with the relation for zero return flow, and that the relative response of the two diaphragms 82 and 90 is also modified.

In order to compensate for the effect which return flow has on the functioning of diaphragms 82 and 90, the third diaphragm 98 is made responsive to fluid flow conditions in the return line 52, as indicated by differential pressures transmitted through tubes 94, 96, the diaphragm 98 acting to oppose the operation of diaphragm

90 and to assist the operation of diaphragm 82; the force exerted by diaphragm 98 being applied to lever 110 and transmitted through pin 108 to lever 102, so that the operation of diaphragm 98 is superimposed on the operation of diaphragms 82 and 90 which normally act to control the supply of raw material in relation to fresh air to maintain a fuel-air ratio of constant value, or of a predetermined range of values, throughout the entire range of pulverizer output capacities. Based on the known pulverizer characteristics as heretofore mentioned, such predetermined values of fuel-air ratios may be obtained by suitable adjustment of the position of diaphragm 98 relative to the fulcrum 104, and by suitable adjustment of the spring 122; the diaphragm adjustment being made for maintaining either a constant or varying fuel-air ratio throughout a given range of pulverizer capacities, and the spring adjustment transposing the value of fuel-air ratio by the same amount for all capacities within the given range. The combination of these two simple adjustments provides a means for securing the desired value or values of fuel-air ratio for the particular arrangement of burners. The return of a proportion of the outgoing mixture to the pulverizer adds to the amount of pulverized material and air flowing through the pulverizer, and accordingly tends to increase the differential pressure across the pulverizer, thereby modifying the normally fixed relation between the differential pressure across the mill 10 and the differential pressure across the air inlet orifice 76. The diaphragm 98 acting in opposition to the pulverizer differential diaphragm 90 serves to cancel out that component of the pressure drop through the pulverizer which is due to the returned pulverized material and air, and enables the operation of feeder 12 to be kept in step with the incoming fresh air as in the case where none of the mixture is circulated and, in consequence, fluid flow through the return line 52 is zero. The differential pressure transmitted through tubes 94 and 96 to the diaphragm 98 need not be of any specific value since a compensating adjustment may be made as at 120 to suitably position the diaphragm relative to the fulcrum 112 for lever 110.

Any number of burners may be cut in or out as desired, and in accordance with operations reported to date, varying loads may be carried with the control apparatus functioning satisfactorily throughout a range as high as 8:1 in pulverizer capacities.

The manner in which movement of the lever 102 is correlated to operation of the feeder motor 16 will be understood from the wiring diagram which by way of example is based on a source of three-phase alternating current supply for operation of an electric motor having separate windings for different speeds. A transformer 128 suitably connected to the main supply lines "AC" provides reduced voltage at its secondary terminals 130 and 132 for the several control circuits, the secondary terminal 130 being connected by lead 134 to the arm 136 of a selector switch 138, the switch arm 136 being shown in the "off" position.

Four adjustably fixed contacts 140, 142, 144 and 146 are shown arranged in pairs at opposite sides of the movable contactor element 106, the contacts 140 and 144 being adjusted to points nearer to the contactor 106 than the contacts 142 and 146, and the contactor 106 being made flexible so that movement of the lever 102 in one direction causes contact to be made first with

contact 140, and then additionally with contact 142. Movement of lever 102 in the opposite direction causes contact to be made first with contact 144 and then additionally with contact 146. Lead 148 connects the contactor 106 with a contact 150 at the "automatic" position of switch 138.

Upper contact 142 is connected to one terminal of the relay coil 152 by lead 154, while upper contact 140 is connected to the same terminal through the normally-open relay switch 156. The other terminal of relay coil 152 is connected to terminal 132 of the transformer secondary by means of lead 158 which serves as the common transformer return connection for the various relay coils shown.

Lower contact 146 is connected to one terminal of the relay coil 160 by lead 162, while lower contact 144 is connected to the same terminal through the normally-open relay switch 164. The other terminal of relay coil 160 is connected to terminal 132 of the transformer secondary through the common connection 158.

A second contact 166 at the "automatic" position of the selector switch 138 is connected by lead 168 to one side of the normally-closed relay switch 170, the other side of which is connected through the normally-open relay switch 172 to one terminal of relay coil 174, and through the normally-closed relay switch 176 to one terminal of relay coil 178. The other terminals of relay coils 174 and 178 are connected to terminal 132 of the transformer secondary through the common return 158.

Switches 180 and 182 are three-pole switches, operated respectively by the relay coils 174 and 178, for establishing connections between the main power supply lines "AC" and the high and low speed windings of the feeder motor 16; a three-wire connection 184 leading from switch 180 to the high speed winding, and a three-wire connection 186 leading from switch 182 to the low speed winding.

When the selector switch 138 is set for automatic operation the motor 16 will operate at low speed as long as contactor 106 is held clear of all contacts 140, 142, 144 and 146. Under such conditions, the relay coil 178 is alone energized, whereby the associated switch 182 is held closed, and power is supplied only through connection 186 to the low speed winding of the motor; the control circuit extending from the transformer terminal 130, through lead 134, switch arm 136, switch contact 166, lead 168, normally-closed relay switches 170, 176, relay coil 178, and return connection 158 to the transformer terminal 132.

Clockwise movement of the lever 102 causing contactor 106 to contact upper contact 140 results in the control circuit voltage being applied to one side of the normally-open relay switch 156. When contactor 106 is brought into contact with upper contact 142, there is a circuit established through the relay coil 152 whereby the associated relay switches 156, 172 and 176 are actuated, and the motor 16 caused to run at high speed. The control circuit in this case is from the transformer terminal 130, through lead 134, switch arm 136, switch contact 166, lead 168, normally-closed relay switch 170, through normally-open relay switch 172 now closed, relay coil 174, and return connection 158 to the transformer terminal 132. The opening of switch 176 opens the circuit through relay coil 178 to interrupt the power supply to the low speed winding, while the closing of switch 172 completes the circuit

through relay coil 174 to close switch 180 and thereby transfer the power supply to the high speed winding. The motor will continue to operate at high speed as long as contactor 106 remains in contact with upper contact 140, whether or not contact is broken with upper contact 142.

Clockwise movement of lever 102 results in similar successive contacting of lower contact points 144 and 146 by contactor 106. When contact is made with point 146 the power supply to the motor 16 is cut off and the motor stops, the contact with point 146 causing relay coil 168 to be energized and the associated relay switches 164 and 170 to be actuated; the opening of normally-closed switch 170 interrupting the control circuit through transformer 128 so that neither relay coil 174 nor 178 is energized and both power switches 180 and 182 remain open.

Additional contacts 188 and 190 may be provided on the selector switch 138 if it is desired to include manual control of motor operation. For this purpose, a connection may be made from contact 188 direct to point 192 of the circuit, and another from contact 190 direct to point 194, whereby low speed or high speed operation may be obtained by moving the switch arm 136 either to contact 188 or to contact 190.

Certain features disclosed herein are also disclosed and claimed in my copending application, Serial No. 531,776, filed April 19, 1944.

The invention as herein disclosed in accordance with the provisions of the statutes will be understood by persons skilled in the art to be applicable in arrangements other than those specifically described, and to include features which may be used to advantage without a corresponding use of other features, within the scope of the appended claims.

I claim:

1. In combination with a pulverizer having an annular grinding zone in a lower portion thereof wherein a reserve of material in the process of pulverization is maintained during normal operation, said pulverizer having an outlet at the upper side of said grinding zone, means for feeding material to be pulverized into said pulverizer above said grinding zone, means forming an annular throat passage marginally of said grinding zone, means for maintaining an upward current of air through said annular throat passage for discharging through said outlet a fluent mixture comprising pulverized material suspended in said air, a main conduit having one end connected to said outlet and having its opposite end open to the interior of said pulverizer at the lower side of said grinding zone, means for withdrawing from said conduit varying proportions of said pulverizer output mixture, said conduit constituting a conductor for returning a remaining proportion of said mixture to said pulverizer at a density substantially equal to the density of the total mixture initially discharged, means separate from said conduit for admitting said air to said pulverizer, means for causing said returned proportion of said mixture to become mingled with said air at a location axially below and adjacent said annular throat passage for combined upward flow through said pulverizer, and means for regulating said material feeding means comprising pressure sensitive means responsive simultaneously to pressure differentials indicative respectively of said air admission to said pulverizer and of said combined fluid flow through a predetermined portion of said pulverizer inclusive of said annular throat passage.

2. In a system of the class described, an air-swept pulverizer having an annular grinding zone within the lower portion thereof in which material in the process of pulverization is maintained during normal operation, said pulverizer having an outlet from its upper portion for discharging a fluent mixture comprising pulverized material suspended in air, means for withdrawing from said system varying amounts of the total mixture discharged from said pulverizer outlet, means for supplying air to said pulverizer at a level below said grinding zone, means separate from said air supplying means for returning to said pulverizer a remaining portion of said mixture at a density substantially equal to the density of the total mixture initially discharged, means for mingling the returned portion of said mixture with said supplied air, means for directing said returned portion mingled with said supplied air upwardly through said pulverizer inclusive of said grinding zone, means for feeding material to be pulverized into said pulverizer above said grinding zone, means for regulating said feeding means comprising pressure sensitive means responsive to a pressure differential indicative of said mingled fluid flow through said pulverizer inclusive of said grinding zone, and means for rendering said regulating means operative in accordance with a measure of the return flow of said remaining mixture portion.

3. In combination with an air-swept pulverizer arranged to discharge a fluent mixture of pulverized material and air, means for feeding material to be pulverized to said pulverizer, means for returning a portion of said mixture to said pulverizer, means for regulating the rate at which said material to be pulverized is fed to said pulverizer, and means responsive to the flow of said portion being returned for controlling the operation of said last named means to maintain a predetermined ratio of air to material in said mixture.

4. In combination with an air-swept pulverizer arranged to discharge a fluent mixture of pulverized material and air, means for feeding material to be pulverized to said pulverizer at varying rates to provide varying output capacities, means for returning a portion of said mixture to said pulverizer, means for regulating the rate at which said material to be pulverized is fed to said pulverizer, and means responsive to the flow of said portion being returned for controlling the operation of said last named means to maintain the ratio of air to material in said mixture substantially constant at said varying output capacities of said pulverizer.

5. In combination with an air-swept pulverizer arranged to discharge a fluent mixture of pulverized material and air, means for feeding material to be pulverized to said pulverizer, means for delivering a portion of said mixture to a point of use, means for returning the remainder of said mixture to said pulverizer, means for measuring the rate at which said remainder is returned to said pulverizer, and means controlled by said last named means for regulating the operation of said feeding means.

6. In a continuous conduit system including a pulverizer, means for supplying material to be pulverized to said pulverizer, means for supplying carrier air to said pulverizer for transporting pulverized material therefrom and through said system, means for withdrawing a portion of said pulverized material and air from a part of

said system other than said pulverizer, means for maintaining another portion of said pulverized material and air in circulation throughout said system, means for regulating the rate at which said material to be pulverized is supplied to said pulverizer, and means responsive to the rate of circulation of said other portion of pulverized material and air for controlling the operation of said regulating means.

7. In combination with an air-swept pulverizer having separate inlets for fuel and air and having an outlet for pulverized fuel mingled with said air, a continuous conduit having one end connected to said pulverizer outlet and its opposite end connected to said inlet for air, means for supplying fuel to said pulverizer, means for withdrawing a portion of said fuel-air mixture from said conduit, means for measuring the rate at which the remaining portion of said mixture is returned to said pulverizer air inlet through said opposite conduit end, and means controlled by said last named means for regulating the rate at which fuel is supplied to said pulverizer.

8. In an air-swept conduit system including a pulverizer, wherein a portion of the mixture of pulverized material and carrier air discharged from the pulverizer is withdrawn from said system and a remaining portion of said mixture is returned to said system for recycling through said pulverizer, the method of controlling the operation of said pulverizer at varying capacities which comprises feeding material to be pulverized to said pulverizer, supplying carrier air to said pulverizer, each from a source outside said system, measuring in terms of differential pressure the rate at which carrier air is supplied to said pulverizer, measuring in terms of differential pressure the rate of fluid flow through said pulverizer, measuring in terms of differential pressure the rate at which pulverized material and carrier air are returned to the pulverizer, and regulating the rate at which material to be pulverized is fed to the pulverizer in accordance with the resulting three measures of differential pressure.

9. In a system of the class described, an air-swept pulverizer arranged to discharge a fluent mixture of pulverized fuel suspended in air, means for supplying fuel to said pulverizer, means for returning a portion of said mixture to said pulverizer and for mingling said portion with air supplied to said pulverizer, means for measuring the rate of air flow to the pulverizer, means for measuring the differential pressure across a predetermined portion of said pulverizer, means for measuring the rate at which said portion of the mixture is returned to the pulverizer, and means conjointly responsive to said three named measuring means for regulation the rate at which fuel is supplied to said pulverizer.

10. In combination with an air-swept pulverizer arranged to discharge a fluent mixture of pulverized material suspended in a stream of carrier air, means for supplying material to be pulverized to said pulverizer, means for returning a mixture of pulverized material and air to said pulverizer at a rate less than the rate at which said initial mixture of pulverizable material and carrier air is discharged from the pulverizer, means for measuring the rate of flow of carrier air to said pulverizer, means for measuring the differential pressure across a predetermined por-

tion of said pulverizer, means for measuring the rate at which said pulverized material and air are returned to the pulverizer, and means under the joint control of said three named measuring means for regulating the rate at which said material to be pulverized is supplied to said pulverizer.

11. In combination with a pulverizer having a grinding zone in a lower portion thereof comprising an annular grinding surface together with a circular row of rollable grinding elements co-operating with said surface, means for feeding material to be pulverized to said grinding zone from above, means forming an annular throat passage marginally of said grinding surface for admitting air into proximity with said grinding zone from below, means for maintaining an upward current of air through said throat passage for discharging from said pulverizer a fluent mixture comprising pulverized material suspended in said air, a main conduit having its opposite ends open to the interior of said pulverizer above and below said annular throat passage, said conduit forming with said pulverizer a closed circulating path for a portion of the total mixture initially discharged from said pulverizer, means for regulating the rate at which said material is fed to said grinding zone comprising means responsive to the rate of air delivery to said annular throat passage relative to the rate of fluid flow through a predetermined portion of said pulverizer inclusive of said annular throat passage, and means for rendering said regulating means operative in accordance with the rate at which said portion of said output mixture is returned to said pulverizer.

12. In combination with a pulverizer having a grinding zone in a lower portion thereof wherein a reserve of material in the process of pulverization is maintained during normal operation, said grinding zone being defined by upper and lower grinding rings and a circular series of metal balls operating therebetween, means for feeding material to be pulverized to said pulverizer above said grinding zone, means forming an annular throat passage interiorly of said lower ring for admitting air to said grinding zone from below, means for maintaining an upward current of air through said throat passage and grinding zone for discharging from said pulverizer a fluent mixture comprising pulverized material suspended in said air, a main conduit having its opposite ends open to the interior of said pulverizer at the upper and lower sides of said grinding zone, said conduit forming with said pulverizer a closed circulating path for at least a portion of the total mixture initially discharged from said pulverizer, means for measuring in terms of differential pressure the rate at which air is delivered to said throat passage, means for measuring in terms of differential pressure the rate of fluid flow through a predetermined portion of said pulverizer including said throat passage and said grinding zone, means for measuring in terms of differential pressure the rate of flow of the portion of said mixture being returned to said pulverizer, and means rendered operative in response to said three named measuring means acting jointly for controlling the rate at which material to be pulverized is fed to said pulverizer.
